UNITED STATES PATENT OFFICE.

HENRY W. YOST, OF DAYTON, OHIO, ASSIGNOR TO THE GRETHER FIRE EQUIPMENT COMPANY, OF DAYTON, OHIO, A CORPORATION OF OHIO.

PLASTER FORK.

Application filed November 24, 1923. Serial No. 676,823.

To all whom it may concern:

Be it known that I, HENRY W. YOST, a citizen of the United States, residing at Dayton, in the county of Montgomery and 5 State of Ohio, have invented certain new and useful Improvements in Plaster Forks, of which the following is a specification.

This invention relates to new and useful improvements in plaster forks, and more 10 particularly to a combination tool of this type for use in fire department service.

It is the principal object of my invention to provide a strong, one-piece tool which may not only be used effectively to pull 15 down ceilings of metal or plaster board and the like to afford access to a fire behind them, but one over the front end of which the metal or board which clings to it may be easily withdrawn.

20 In forks of this type as at present constructed, it is difficult to pull the clinging metal or other substance from the front end because of the interference offered by the pivoted knives or ears and other projecting 25 parts of the tool, but in my improved fork the knives are free to be drawn inwardly a sufficient distance to permit the clinging substance to clear them. The operation of pulling 30 the clinging metal or other substance over the knives is assisted by curved fillets which are placed just beyond the latter to act as guides to deflect the clinging material outwardly in an even manner for removal over the arrowhead portion of the tool.

35 It is still another object of the invention to provide means for holding the knives in their closed positions during the removal of the clinging material from the tool.

It is still a further object of my invention 40 to provide means for preventing the clinging material from working down over the handle of the tool.

Other important and incidental objects 45 will be brought out in the following specification and particularly set forth in the subjoined claims.

In the accompanying drawings illustrating 50 my invention, Figure 1 is a side, elevational view of my improved plaster fork. Figure 2 is a front view, in section, of the same. And Figure 3 is a front elevational view of the tool, showing the knives or ears in their closed positions.

Throughout the specification and draw-

ings, similar reference characters denote 55 corresponding parts.

Referring to the accompanying drawings for a detailed description of my invention, the numeral 1 designates a tubular member made of tool steel or other suitable material. 60 The outer part 2 of this member is flattened, terminating in a truncated arrow-head portion 3. In the outer end of the latter there is a threaded axial recess which receives the threaded stem 4 of a hard, pointed insert 5 65 which forms with the portion 3 of the member 1, a complete arrow-head. This insert 5 is sufficiently hard and sharp to penetrate a metal or plaster ceiling or siding for the passage therethrough of the pivoted knives 70 or ears now to be described.

The flattened portion 2 of the member 1 contains a longitudinal slot 6 which extends from one side of the latter to the other between a raised web part 7 on the inner wall 75 of said member and its arrow head portion 3. Pivotal secured by pins 8, 8 within the longitudinal slot 6 of the member 1, so that they may close therein, are two outwardly 80 projecting knives or ears 9, 9 which are preferably constructed of tool steel and of the shape shown in Figure 2. The inner ends of these knives are round, the arrowhead portion 3 of the member 1 being recessed to receive them when their outer ends, 85 which are pointed, are moved into the slot 6 against the web portion 7 of the inner wall of said member. (See Figures 2 and 3.)

Free to move through a hole in the middle part of the web 7 in the member 1, is a 90 plunger 10 having its outer end externally threaded to receive a cap 11 to the sides of which are pivotally secured links 12, 12. At their outer ends these links are pivotally secured in recesses in the lower, inner corner 95 parts of the knives 9, 9, so that when the links are moved outwardly by the plunger 10, they will force the knives 9, 9 into the slot 6 for a purpose to be hereinafter described.

100 Referring to Figure 2, the tubular member 1 has its inner portion pipe-threaded to receive the threaded end of a tubular handle 13. The latter is covered by a sleeve 14 of rubber or other insulating material to protect the user against electric shocks. At its inner end the sleeve 14 fits against an annular shoulder 15 formed within a bead 16

on the inner end of the tubular member 1. This bead or rib 16, which encircles the inner end of the tubular member, prevents any material which has been speared thereon, from working down on the handle 13. Cemented to the outer end of the latter is a semi-hard rubber cap 17 in which there is an annular groove 18 to tightly fit both the outer end of the handle 13 and the insulating sleeve 14. (See Figures 2 and 3.)

The cap 17 has a countersunk middle portion 19 containing two axial holes 20 and 21, the hole 20 being of larger diameter than the hole 21. Free to pass through either of said holes is a cable 22. The latter is connected, within the middle portion of the handle 13, to one end of a helical spring 23, the other end of which is secured to a cable 24. (See Figure 2.)

Secured within an annular recess in the interior portion of the tubular member 1, by a screw 25, is a plug 26 in the middle of which there is a bearing hole through which the plunger 10 projects into the tubular handle 13. Provided in the inner end of the plunger is a cross drilled hole 27 which communicates with an axial hole to receive through the latter the inner end of the cable 24 after it passes over a roller 28 on a pin 29 secured in a slot 30 within the plug 26. (See Figure 2.)

Surrounding the plunger 10 between a collar 31 thereon and the web portion 7 in the tubular member 1, is a helical spring 32 which works in opposition to the spring 23. When the cable 22 is pulled outwardly, the plunger 10 will be elevated or moved outwardly by the cable 24 against the compression of this spring 32, to force the knives 9, 9 into the slot 6 in the tubular member 1 as shown in Figure 3. Since the links 12, 12 are secured to the knives by pins 33, 33 in the recessed portions of the latter, the inward movement of the knives will not be obstructed by the links. (See Figures 2 and 3.)

In order to hold the knives in their closed positions, there is secured on the cable 23 a small ball 34 between two larger balls 35 and 36 on said cable. The ball 34 is of such a size as to pass freely through the hole 20 in the cap 17, so that it may be brought beneath the small hole 21, which is of smaller diameter than the ball. Between the holes 20 and 21, there is formed in the cap 17 a transverse slot 37 through which the cable 22 is adapted to be drawn to bring the ball 34 directly below the hole 21. The spring 23 will, by virtue of its yielding quality, assist in the adjustment of the ball 34 beneath the hole 21.

Since the ball 34 cannot be drawn through the hole 21 in the cap 17, the knives 9, 9 will be held in their closed positions by it until the cable 22 is shifted through the

slot 37 into the hole 20, whereupon the ball will be free to pass through the latter to permit the compressed spring 32 to force the knives 9, 9 outwardly to their right-angled positions. The ball 35, which is larger than the hole 20, is secured to the cable 22 to limit the outward movement of the latter, the inward movement of it being limited by the ball 36 which is also larger than said hole. (See Figures 1 and 2.)

Just below its arrow-head portion 3, there is provided on each side of the tubular member 1 a fillet 38 which forms a surface that curves outwardly in a regular manner to said arrow-head portion, thereby to assist in the removal of any material that clings to said tubular member after it has been forked thereby. (See Figures 2 and 3.)

When it is desired to get at a fire behind a ceiling or siding of metal, plaster board or the like, my improved fork is first used to penetrate the same by thrusting therethrough its pointed insert 5. The passage of the outer end of the fork through the material of which the ceiling or siding is made, will force the knives 9, 9 inwardly against the compression of the spring 32 on the plunger 10. Then, when the dismantled material is no longer beyond them, these knives, being individually fulcrumed, will be readily moved to their right-angled positions by the expanding spring acting upon the plunger 10, so that they may serve as gripping elements to pull out that portion of a ceiling or siding that prevents access to the fire. My improved fork may also be used with equal facility in dismantling a building in which no fire has occurred.

The dismantled material which clings to the fork after the latter has been forced through it, cannot work down on the handle 13 because of the barrier which the bead 16 forms to its movement in that direction. It can be easily removed from the front end of the tool, however, in the following manner. The cable 22 is pulled outwardly a sufficient distance to move the plunger 10 to a point where the links 12, 12 will be acted upon by it to force the knives 9, 9 into the slot 6 in the tubular member 1. The material on the fork below these knives is now free to be pulled over them to the fillets 38, 38, whose curved surfaces guide said material over the arrow-head portion 3 of the fork.

During the operation of removing the dismantled material, the knives are held firmly in their closed positions by shifting the cable through the slot 37 to the hole 21 in the cap 17, so that the ball, by its engagement in the lower end of said hole, will resist the expansion of the spring 32. (See Figure 3.) As soon as the dismantled material is removed from the tool, the cable

22 by being shifted through the slot 37 in the cap 17 to the hole 20 therein, will permit the ball 34 to pass through the latter so that the spring 32 may return the knives 5 9, 9 to their right-angled positions. This will be accomplished with ease through the action of the links 12, 12 upon the inner ends of the individually fulcrumed knives.

It will thus be seen that I have provided 10 a one-piece combination tool which may not only be used effectively to pull down a ceiling or siding of metal, plaster board and the like, but one from which the material which clings to it may be easily removed 15 over its front end.

I do not wish to be limited to the details of construction and arrangement herein shown and described, and any changes or 20 modifications may be made therein within the scope of the subjoined claims.

Having thus described my invention, I claim:

1. In a device of the type described, the combination with a pointed member, of a 25 pair of knives fulcrumed therein behind its pointed end and adapted to be moved outwardly at an angle thereto, a spring adapted to normally hold said knives in a distended position, and means connected to said knives 30 for operation in opposition to said spring to force them into a closed position.

2. In a device of the type described, the combination with a pointed tubular member having a slotted outer end, a pair of knives 35 separately fulcrumed at their inner ends within the slotted portion of said tubular member, a spring within said member adapted to normally hold said knives in a distended position, and means within the 40 tubular member, operable in opposition to said spring, to force said knives within its slotted portion for the purpose specified.

3. In a device of the type described, the combination with a pointed tubular member 45 having a slot in its outer end, of a pair of knives separately fulcrumed at their inner ends within said slot, a spring within said member adapted to normally hold said knives at an angle thereto, and means connected to the inner ends of said knives within the tubular member, and operable 50 through its inner end, to force them into said slot against the compression of the spring for the purpose specified.

55 4. In a device of the type described, the combination with a pointed tubular member having a slot in its outer end, of a pair of knives separately fulcrumed at their inner ends within said slot, a plunger longi-

tudinally movable in said tubular member, a 60 pair of links connected between the plunger and the inner ends of said knives, a web in said tubular member through which said plunger projects, a collar on said plunger below the web, a helical spring on the 65 plunger between the web and the collar, a plug in the inner portion of the tubular member through which the plunger projects, a roller pivotally secured within said web, and a cable connected to the lower end of 70 the plunger and passing over the roller for the purpose specified.

5. In a device of the type described, the combination with a tubular member, of a 75 pair of knives pivoted within said member for outward movement at an angle thereto, a spring for normally holding said knives distended, means within said member and operable from its lower end for pulling the outer ends of the knives within the tubular 80 member against the compression of said spring, and means for holding the knives in their closed positions.

6. In a device of the type described, the combination with a tubular member, of a 85 pair of knives pivoted within said member for outward movement at an angle thereto, a spring for normally holding said knives distended, a tubular handle secured to the inner end of said tubular member, a cap 90 containing two different-sized axial holes connected by a transverse slot, applied to the outer end of the handle, a cable for pulling said knives inwardly against the compression of said spring, said cable being free to pass through either one of said holes and the slot, and a ball on said cable adapted to pass through the larger hole but not through the smaller one, for the purpose 95 specified.

7. In a device of the type described, the combination with an arrow-head member, of a pair of knives pivoted thereto behind its arrow head portion and adapted to be moved to a position at an angle to said member, a spring for holding said knives in a distended position, means for closing the knives against the compression of said spring, and a fillet between each knife and the arrow-head portion of said member to assist in the removal of the dismantled material from the front end of it when the knives are closed.

In testimony whereof I have hereunto set my hand this 1st day of November, 1923.

HENRY W. YOST.

Witness:

HOWARD S. SMITH.
